COSTUME JEWELRY

Mario Lely, New York, N. Y.

Application September 4, 1935, Serial No. 39,090

8 Claims. (Cl. 63—2)

This invention relates to costume jewelry and has particular reference to improved means for attaching one or more ornaments to an article of wearing apparel.

5 The invention broadly contemplates in an article of the character described, one or more coiled contractile clips of any desired configuration and means continuous therewith constituting a guide for facilitating the insertion of the article 10 decorated thereby.

The invention further provides an attaching clip comprising coiled contractile opposite end portions having ornaments mounted thereon with inter-engageable means for releasably attaching 15 the ornaments together and guide means for facilitating the application of the clip to an article of wearing apparel.

The invention further resides in an article of 20 costume jewelry including coiled contractile opposite end portions and an intermediate connecting portion continuous therewith providing a guide for facilitating the attachment of the contractile end portions to an article of wearing apparel.

25 Other objects of the invention reside in the provision of articles of costume jewelry which are not unduly complicated in their construction or mode of use, which may be economically produced and which are highly decorative and effective.

With these and other objects in view, the invention is more particularly set forth in the specification and drawing wherein there are disclosed several embodiments of the invention, 35 while the claims cover other variations and modifications falling within the scope of the invention.

In the drawing:

Fig. 1 illustrates an article of costume jewelry constructed in accordance with the invention in applied position to a garment.

Fig. 2 is a rear view thereof.

Fig. 3 is a sectional view therethrough taken approximately on the line indicated at 3—3 in Fig. 2.

45 Fig. 4 is a plan view of the same.

Fig. 5 is a rear view illustrating a modified form of the invention.

Fig. 6 is a side edge view thereof.

Fig. 7 is a rear view of another form of the 50 invention.

Fig. 8 is a perspective view of a further modification.

Referring to the drawing by characters of reference and particularly to the form of the invention illustrated in Figs. 1 to 4 inclusive, 10

and 11 designate respectively coiled contractile clips constructed from a length of resilient wire and preferably formed integral with a substantially V-shaped connecting portion 12 which constitutes a guide for facilitating the engagement 5 of the same with an article of wearing apparel A which is adapted to be clamped between the connecting portion 12 and the coils 10 and 11.

As shown, the divergent arms 14 and 15 of the connecting portion 12 extend diagonally across the coiled contractile portions 10 and 11 with the bight 16 of said portion 12 protruding beyond the confines of the coiled portions. The terminals 17 preferably carry ornaments 18 which, as illustrated, are of spherical form and lie partially 15 within the confines of the coils. If desired, the wire may be further decorated with beads or other ornamental elements 19 strung thereon to obtain a decorative effect as shown in the drawing.

20 The article may be employed for various purposes such as an ornament for a dress, an ornamental clasp for securing together scarfs, as an ornament for a hat, belt or any other article of wearing apparel.

25 In the form of the invention illustrated in Figs. 5 and 6, the coiled contractile portions 20 and 21 which are joined by the V-shaped connecting portion 22 have hingedly connected to the forward convolutions thereof, ornamental or decorative 30 elements 23 and 24 which permit of the swinging of the same with reference to the coiled portions 20 and 21. This arrangement permits of the 35 swinging of the decorative elements 23 and 24 away from the coils and connecting portion 22 to facilitate the engagement and disengagement of the coils with the garment or other article of 40 wearing apparel.

In the form of the invention shown in Fig. 7, the device which is similar to that illustrated in 40 Figs. 5 and 6 is disclosed as having the decorative or ornamental articles 23 and 24 provided with separable means of connection in the form of a coupling having a resilient clasp 26 and keeper 27 provided respectively on said elements.

45 In the form of the invention shown in Fig. 8, a single coil 28 is provided which has hingedly attached to the terminal of one end convolution thereof a decorative element 29, while the terminal of the other end convolution is bent into substantially U-shaped form as at 30 and extends 50 between adjacent convolutions with the bight portion 31 protruding beyond the confines of said convolutions to provide a guide for facilitating 55

the engagement of the device with a garment or other article of wearing apparel.

In its various forms the article of jewelry may be employed in various ways and in some instances it may be utilized for securing together 5 the parts of a garment or the ends of a scarf, while it is readily adjustable with reference thereto and firmly fastened in place thereon against accidental or unintentional displacement.

10 What is claimed is:

1. A costume ornament including resilient coiled contractile opposite end portions each including a plurality of convolutions arranged in different planes and adapted to secure therebetween an article of wearing apparel and an intermediate portion joining said end portions, said intermediate portion being bent to substantially V formation extending beyond the confines of 15 said end portions to provide a guide for facilitating the insertion of an article of wearing apparel between said intermediate portion and said contractile end portions.

2. A costume ornament including resilient coiled contractile opposite end portions each including a plurality of convolutions with adjacent convolutions of each end portion arranged in different planes and adapted to secure therebetween an article of wearing apparel, ornamental means secured to the said end portions and an intermediate portion joining said end portions and providing a guide for facilitating the attachment of said costume ornament to an article of wearing apparel.

3. A costume ornament including resilient coiled contractile opposite end portions adjacent convolutions of which end portions are arranged in different planes, an ornament secured to the front convolutions of said end portions and an intermediate portion joining the rear convolutions of said end portions, said intermediate portion being rebent to provide a guide for facilitating the attachment of an article of wearing apparel between said intermediate portion and said contractile end portions.

4. A costume ornament including coiled contractile opposite end portions adjacent convolutions of which end portions are arranged in different planes, an ornament hingedly secured to the front convolutions of said end portions and

an intermediate portion joining the rear convolutions of said end portions, said intermediate portion being bent to substantially V formation extending beyond the confines of the said contractile end portions to provide a guide for facilitating the attachment of an article of wearing apparel to said contractile end portions. 5

5. A costume ornament including a resilient coiled contractile body including a plurality of convolutions adjacent convolutions of which are arranged in different planes, a decorative element hingedly secured to the front convolution thereof and a rebent portion continuous with said contractile body and providing a guide for facilitating the attachment of an article of wearing apparel to said contractile body. 10

6. A costume ornament including coiled contractile opposite end portions adjacent convolutions of which end portions are arranged in different planes, an ornament secured to the front convolution of each of said end portions and interengageable means on said ornaments for releasably attaching the same together and an intermediate portion connecting said opposite end portions providing a guide for facilitating the attachment of an article of wearing apparel to said end portions. 20

7. A costume ornament including a body consisting of a length of resilient wire having coiled contractile opposite end portions each of which end portions is adapted to clampingly engage portions of an article of wearing apparel to be decorated thereby and an intermediate portion joining said end portions providing a guide for facilitating the attachment of each of said end portions to the article of wearing apparel, and ornamental means secured to said body and located intermediate the ends thereof. 30

8. A costume ornament including a body consisting of a length of resilient wire having oppositely arranged contractile gripping means for attaching the same to portions of an article of wearing apparel, and a connection between said gripping means constituting a guide for facilitating the engagement of said gripping means with the article of wearing apparel, and a decorative element secured to the body. 40
